COMPACT COOLING UNIT

Alfred P. Brandimarte, Fort Worth, Tex., assignor to
A.R.A. Manufacturing Company, Grand Prairie, Tex.,
a corporation of Texas

Filed Oct. 28, 1959, Ser. No. 849,263
2 Claims. (Cl. 62—427)

This invention relates to refrigeration evaporator coils and has reference to construction of cooling coil units for installation in recessed areas.

The operation of cooling coils with associated air driving systems in recessed spaces often presents special problems in the attainment of both adequate air circulation and sufficient cooling. Where a cooling unit is to be installed beneath the dashboard of an automobile, for example, useful circulation may be restricted to three directions and the height of the available installation space may greatly limit the diameter of a fan positioned perpendicular to any direction of circulation.

An object of the present invention is to provide a cooling coil construction for installation in a confined area and wherein a simple and economical arrangement of components may be used to provide efficient circulation and cooling of air.

Another object of the invention is to provide a construction for cooling units wherein a single motor may be used to drive two fans or two combination wheels in sirocco type wheel housings and produce a desirable air circulation pattern in an area to be cooled.

A further object of the invention is to provide a cooling unit of the class described and wherein its air discharge pattern may be adjusted or modified to meet particular requirements.

Another object of the invention is to provide a construction for a cooling unit adapted for installation in a dimensionally restricted space and wherein circulated air may be passed twice over a cooling surface in an internal flow pattern.

These and other objects will become apparent from the following description and the accompanying drawings, wherein:

FIGURE 1 is a sectional plan view of the invention.

FIGURE 2 is a partially sectional front elevational view of the invention.

FIGURE 3 is a sectional view taken on line 3—3 of FIGURE 1.

In the drawings, a rectangular box like housing 10 is shown with its height as its smallest dimension and with its width greater than its depth; hence, the upper and lower walls 11 and 12 of the housing 10 constitute its largest bounding surfaces whereas the forward and rear walls 13 and 14 are smaller in area than the upper and lower walls, and the side walls 15 and 16 are smaller than the forward and rear walls. The illustrated configuration of the drawing 10 conforms generally to the space available for installation of a cooling unit in a laterally disposed recess as beneath the dashboard of an automobile, and it is assumed for purposes of the present description that the upper, lower and rear walls 11, 12 and 14 are confined by the boundaries of an installation space and are available as passageways for air circulation. Within the housing 10 an electric motor 17, including oppositely projecting shafts 18 and 19, is mounted medially between the side walls 15 and 16 and is spaced from the upper, lower, forward and rear walls 11, 12, 13 and 14 with its shafts 18 and 19 projecting equidistantly toward the side walls 15 and 16. Fans 20 and 21 are respectively secured to the projecting ends of the shafts 18 and 19 and blades of the two fans are oppositely pitched so that operation of the motor 17 will cause each fan to impel air inwardly toward the motor as indicated

2

by arrows in FIGURE 1. It will be noted that rearrangement of the fans 20 and 21 may be utilized to effect a reversal of air flow from that described above and shown in FIGURE 1. If blower type impeller wheels in sirocco housings are used instead of fans, the air flow is only as indicated in FIGURE 1.

A U-shaped evaporator coil 22 is also mounted within the housing 10 and is there oriented with its central or closed portion inwardly adjacent the forward wall 13 of the housing 10 and with its opposite ends projecting rearwardly so as to be substantially parallel with the side walls 15 and 16. The evaporator coil 22 is shown in a conventional form of construction and has a plurality of horizontal evaporator tubes 23 passing through a plurality of vertically disposed heat exchange fins 24; U-joints 25 communicate the ends of adjacent evaporator tubes 24 to form a closed evaporator system between a suction manifold 26 and an intake manifold 27. The suction manifold 26 projects laterally and exteriorly of the housing 10 where it is provided with a fitting 28 for connection with the low pressure side of a refrigerant pump (not shown). An expansion valve 29 is positioned within the housing 10 rearwardly of the motor 17 and communicates its low pressure side with the intake manifold 27 through a union 30. A liquid line 31 (FIGURE 2) communicates with the high pressure side of the expansion valve 29 and projects exteriorly of the housing 10 where it is provided with a fitting 32 for connection with a condenser (not shown).

30 Lateral partitions 33 and 34 extend vertically between the upper and lower walls 11 and 13 of the housing 10 and are positioned forwardly of the respective fans 20 and 21 where they extend laterally from the inner sides of the evaporator coil 22 to the respective planes of rotation of the fans 20 and 21. Lateral partition extensions 33a and 34a respectively extend, in alignment with the lateral partitions 33 and 34, from the outer sides of the evaporator coil 22 to the side walls 15 and 16 of the housing 10. Shroud plates 35 and 36 integrally formed as continuations of the respective lateral partitions 33 and 34 extend rearwardly in the respective planes of rotation of the fans 20 and 21. Circular openings 37 and 38 are provided in the shroud plates to accommodate the fans 20 and 21. Cylindrical shrouds 39 and 40 may be mounted within the periphery of each circular opening 37 and 38. Deflection partitions 41 and 42, constructed as continuations of the respective shroud plates 35 and 36, are formed arcuately, inwardly and forwardly from the rearward extremities of the shrouds 39 and 40 to the central periphery of the motor 17 where the deflection partitions are joined by a vertical juncture plate 43. Deflection partitions 41a and 42a extend laterally and outwardly from the respective rearward extremities of the shroud plates 35 and 36 to the side walls 15 and 16 of the housing 10. A divider partition 44 extends from the center of the U-shaped evaporator coil 22 to the juncture plate 43 where it is provided with a flange 45 attached to the forward surface of the juncture plate. The rearward termination of the divider partition 44 and forward portions of the deflection partitions 41 and 42 and the juncture plate 43 are recessed to circumstantially accommodate the motor 17.

Intake ports 46 and 47 are formed in opposite side walls 15 and 16 of the housing 10 at positions therein in lateral alignment with the fans 20 and 21. A rectangular air discharge grill 48 including stationary horizontal louvers 49 is formed in the forward wall 13 of the housing 10 and projects forwardly of the remainder of the forward wall. Within the rectangular air discharge grill 48 a plurality of circular openings 50, each defined by a peripheral lip 51, are arranged in coplanar relationship with one another and with the rectangular grill. A ro-

tatable circular grill 52 defined by a cylindrical bearing surface 53 is positioned within each circular opening 50; an annular flange 54, larger in diameter than the circular opening 50 is formed on the rearward edge of each cylindrical bearing surface and is positioned rearward of and adjacent the peripheral lip 51 in the rectangular grill 48.

In operation, the fans 20 and 21 are set in rotation by the motor 17 and the evaporator coil 22 is cooled by expansion of an internal refrigerant as is well known in the art. One fan 20 impels air into the housing 10 through a corresponding intake port 46 and the air thus impelled is drawn through an end portion of the U-shaped evaporator coil 22. The lateral portion 33, shroud plate 35, deflection partition 41 and divider partition 44 define an internal compartment forwardly bounded by a portion of the evaporator coil 22 not utilized as a cooling surface in the original introduction of air into the housing 10. Air which has passed through the shroud 39 is forwardly deflected by the deflection partition 41 and passed over a different part of the evaporator coil 22 before being expelled from the housing 10 through the discharge grill 48. In like manner, the other fan 21 impels air through an intake port 47; through an end portion of the evaporator coil 22 and then over a central portion of the evaporator coil before expelling cooled air through the discharge grill 48. Thus, the respective fans 20 and 21, driven by a single motor 17, draw air through intake ports 46 and 47 in opposite sides of the housing 10 and each expels air forwardly through the discharge grill after it has been twice exposed to cooling surfaces. In passing through the housing 10 air is subjected to a single 90° change in direction of flow regardless of which intake port it enters; deflection partitions 41 and 42 minimize turbulence in this flow pattern.

The invention is not limited to the exemplary construction herein shown and described, but may be made in many ways within the scope of the appended claims.

What is claimed is:

1. A cooling unit comprising: a box-like housing including a forward wall and side walls; air intake ports in said side walls of said housing; an exhaust port substantially coextensive with said front wall of said housing; a U-shaped evaporator coil positioned within said housing and having its end portions adjacent said air

intake ports in said side walls and having a central portion adjacent said exhaust port in said front wall, a motor positioned within said housing and including shafts projecting oppositely therefrom toward said side walls, 5 fans pitched oppositely with respect to one another and respectively attached to said shafts, partitions respectively extending from a position on said U-shaped evaporator coil forward of each fan to the plane of rotation of each fan and thence rearwardly in the plane of rotation of each fan beyond the rearward extent of each fan and thence arcuately inwardly and forwardly to the central periphery of said motor, openings in said partitions to accommodate said fans, shrouds within said openings in said partitions, and a central partition extending forwardly from the central periphery of said motor to said central portion of said evaporator coil.

2. A cooling unit comprising: a housing including a front wall and side walls; intake ports in said side walls, an exhaust port in said front wall; a cooling element positioned within said housing and having ends thereof positioned adjacent said intake ports in said side walls and having a central portion thereof adjacent said exhaust port, a motor positioned within said housing and having shafts projecting oppositely toward said end portions of said cooling element, fans pitched oppositely with respect to one another and respectively attached to said shafts, shrouds respectively positioned about said fans and extending therefrom to said end portions of said cooling element, and means forwardly deflecting air from said shrouds to said central portion of said cooling element, said means comprising arcuate vertical partitions respectively extending from the rearward extremities of said shrouds inwardly and forwardly to the central circumference of said motor, and a central partition extending forwardly from the central periphery of said motor to said central portion of said cooling element.
